UNITED STATES PATENT OFFICE.

FRANK M. LEAVITT, OF NEW YORK, N. Y., ASSIGNOR TO E. W. BLISS COMPANY, OF BROOKLYN, NEW YORK, A CORPORATION OF WEST VIRGINIA.

IGNITION DEVICE FOR AUTOMOBILE TORPEDOES.

No. 880,029.

Specification of Letters Patent.

Patented Feb. 25, 1908.

Application filed February 16, 1907. Serial No. 357,629.

To all whom it may concern:

Be it known that I, FRANK M. LEAVITT, a citizen of the United States, residing in the borough of Brooklyn, county of Kings, city 5 and State of New York, have invented certain new and useful Improvements in Ignition Devices for Automobile Torpedoes, of which the following is a specification.

This invention relates to automobile torpedoes which are propelled by an engine or motor driven by a charge of compressed air the energy of which is increased by burning a combustible in such manner as to heat the air. The ignition of this combustible should 10 be effected upon or soon after the launching of the torpedo, and shortly after the starting of the engine or motor. Suitable igniting mechanisms for accomplishing this result are set forth in my United States Patents Nos. 20 693,872 dated February 25, 1902 and 825,914 dated July 17, 1906.

The present invention provides an improvement upon the igniting devices set forth in said patents.

According to the present invention the igniter cannot be operated until the engine or propeller shaft has made a predetermined number of turns. Accordingly it is impossible for the igniter to be prematurely operated whereby it might fail to ignite the combustible charge.

In the accompanying drawings,—Figure 1 is a vertical section of the middle portion of a torpedo, showing generally the parts pertaining to the present invention; Fig. 2 is a vertical mid-section on a larger scale of the igniting mechanism; Fig. 3 is a detail on a larger scale of the means for setting the igniter in operation from the engine or propeller shaft; Fig. 4 is a section similar to Fig. 2 but showing the parts after operation. Fig. 5 is a fragmentary section showing a modification.

Referring to Fig. 1, A designates the compressed air reservoir or flash, from which by a suitable pipe *a* compressed air is conveyed to the motor or engine B, the latter being here shown as a fluid pressure turbine. This turbine drives (either directly or through gearing contained in a housing B') the propeller shaft A'. The pipe *a* ordinarily leads through a charging valve *a'* and a starting valve *a''* shown in dotted lines. C is a chamber containing the combustible, usually alcohol, which it feeds through a pipe *b* into a

receptacle D wherein the combustion occurs. As shown, this receptacle is conveniently located in the reservoir A, although it may be placed anywhere where the burning of the combustible may serve to heat the compressed air and expand it before it reaches the engine. H is the igniter, which comprises a cartridge *r* located in the receptacle D, where as it burns it will ignite the combustible therein. For operating the igniter, 60 a lock or cocking mechanism J is provided, which comprises a shell I having a cap P which when removed permits the insertion of the igniter through this shell and through a tube *s* into the receptacle D. The igniter 65 comprises a tube *s* carrying at its lower end the slow-burning cartridge *r* having a percussion cap *r'*; within the tube *s* moves a firing-pin Q having a head Q' which is pressed down by a spring S, but when set (Fig. 2) 70 is held by a tooth *l* which acts as a trigger-sear. This tooth is conveniently formed on a plunger L working as a piston in a cylindrical chamber formed in the shell I, and normally pressed down by a spring *e* which reacts 75 against the cap *k*. When the igniter is first inserted, the head Q' of its firing-pin is stopped against the tooth *l*, and as the cap P is screwed down the spring S is compressed (see Fig. 2); the igniter is operated by pushing up the plunger L (as hereinafter described), thereby withdrawing the tooth *l* so that the spring S throws down the firing-pin Q and explodes the cap *r'* causing the cartridge *r* to burn and igniting the alcohol in 80 the receptacle D. As the heated compressed air flows out from the reservoir A to the engine, the diminution of pressure permits the compressed air above the liquid in the chamber C to expel a continual stream 85 of alcohol, which continues to burn during substantially the entire run of the torpedo.

As thus far described the present construction does not differ from those set forth in my said previous patents.

According to my present invention the plunger L is operated by a difference in fluid pressures above and beneath it, which difference is determined by an escape of pressure caused by a predetermined movement 105 or run of the engine. To accomplish this result in a simple manner, a chamber or space V' beneath the plunger is made to serve as a pressure chamber, while the chamber or space V above it serves as a relief 110

chamber. In charging the reservoir A with compressed air, the latter is admitted in any suitable way to the chamber V'. Thus, this chamber may be permanently connected to the reservoir A; or, as shown in Figs. 2 and 4, it is in communication with the tube d by a minute bore or duct v', so that the compressed air freely passes up through the tube d and into the shell I, and through the duct v' into the chamber V'. At the same time compressed air is admitted also to the chamber V, preferably through a minute bore v, thus establishing therein a pressure equal to that in V'. In place of the bores v v', the plunger may be made a loose fit, so that the leakage around it may serve the same purpose. Thus the plunger L is balanced between the equal pressures above and below it. The chamber V' may be permanently connected with the reservoir by a bore v' as shown in Fig. 5.

The chamber V communicates by a small tube or duct w with an escape device Y operated from the engine by a device Z. The escape device Y might be any sort of relief valve adapted to be opened with certainty by the operation of the part Z; but as such valves are somewhat unreliable, I prefer to make the relief device Y a frangible or puncturable part, and to construct the operating device Z as a knife, cutter, or punch which will break or cut the part Y. This construction is clearly shown in Fig. 3, where the part Y consists of a copper or other soft metal capsule or diaphragm which is confined by a clamp or union y against the end of the tube w. The cutter Z is connected in any suitable manner with the engine, so as to be operated after the engine has executed a certain predetermined run, or in other words, has made a definite number of turns. A convenient way of accomplishing this result is that shown in Fig. 1, where a worm x is provided on the propeller shaft A' and drives a worm wheel z which carries the cutter Z. By setting the wheel z or the cutter thereon so that the latter is backed off a certain distance from the frangible capsule Y, it is easy to determine the number of turns the propeller shaft must make before the cutter shall encounter and break the capsule Y.

The operation is as follows:—Upon launching the torpedo, its engine is started by the operation of a starting valve in the ordinary manner. As the engine runs, compressed air flows from the reservoir to the engine and consequently the pressure in the reservoir diminishes, and as it falls below the air pressure in the chamber C the alcohol begins to flow over from this chamber into the receptacle D. It is now ready for ignition. The preliminary run of the engine carries the cutter Z through its first idle movement until it encounters the capsule Y, and cuts, breaks

or punctures it, thereby permitting the pressure to escape from the tube w and the chamber V. Thus the pressure in V falls below that in the chamber V' and (the minute duct v being too small to quickly restore or equalize the pressure) the preponderant pressure in V' forces up the plunger L against the stress of its spring e, and thereby removes the tooth l from the head Q' and consequently permits the firing pin to act and explode the cartridge and ignite the combustible in the receptacle D. To restore the parts for another operation, it is necessary to renew the cartridge r and cap r'; to reset the igniter; to refill the chamber C with alcohol; to replace the broken capsule Y with a new one; and to reset the wheel z or cutter Z with the latter sufficiently removed from the capsule to provide for the desired number of turns of the engine. A new charge of compressed air must of course be forced into the reservoir.

With this apparatus it is impossible to operate the igniter before the requisite supply of combustible shall have entered the receptacle D, because in setting the cutter Z provision is made for a sufficient duration of run of the engine to insure against this possibility. The plunger L is operated with mathematical certainty by the sudden escape of pressure above it, and the consequent forcible expansion of the air beneath it. The breaking of the capsule Y affords a certain means of insuring the liberation of pressure above the plunger.

The invention is susceptible of considerable modification in details of construction and mode of application. For example it is not essential that the moving part which operates the tooth or trigger-sear l shall take the form of a plunger L; nor that the frangible part Y shall take the form of a cap or capsule, since any easily breakable wall of sheet metal or other frangible or puncturable material might be used. The present invention does not require that the combustible be forced over from the chamber C into the receptacle D; nor that the combustible be liquid; nor that the ignition be effected by a cartridge operated by a percussion cap; nor that the igniter involve a firing pin, as any movable part released by any part in the nature of a trigger will be applicable with this invention.

I claim as my invention:—

1. In an automobile torpedo, the combination of a heater for compressed air, an igniter in said heater, and means for operating the igniter comprising a part movable through a prescribed space before it reaches its operative position, and engine connections for moving said part through such space while the engine is executing a predetermined number of revolutions.

2. An ignition mechanism for an automobile

bile torpedo comprising a movable part restrained by fluid pressure, and means operated by the engine for relieving the pressure to permit the movement of said part.

5. An ignition mechanism for an automobile torpedo comprising a shell, a movable part therein, means for admitting fluid pressure thereto on opposite sides of said part, and means operated by the engine for relieving the pressure to permit the movement of said part.

10. An ignition mechanism for an automobile torpedo comprising a movable part restrained by fluid pressure, means for relieving the pressure to permit movement of said part, and a connection with the engine adapted to operate said means upon a prescribed movement of the engine.

15. An ignition mechanism for an automobile torpedo comprising a movable part restrained by fluid pressure, means for relieving the pressure to permit movement of said part, and reducing gearing connecting said means with the engine to operate it upon a prescribed movement of the engine.

20. An ignition mechanism for an automobile torpedo comprising a pressure-operated movable part, a frangible part adapted to confine the pressure, and means operated by the engine for rupturing said part to permit the escape of pressure.

25. An ignition mechanism for an automobile torpedo comprising a shell, a movable part therein, means for admitting fluid pres-

sure thereto on opposite sides of said part, 35 a frangible part adapted to confine the pressure on one side thereof, and means operated by the engine for rupturing said part to permit the escape of pressure.

3. An ignition mechanism for an automobile torpedo comprising a shell, a plunger therein, means for admitting fluid pressure to opposite sides of said plunger, a frangible part communicating with one side thereof, and means for rupturing said part.

4. An ignition mechanism for an automobile torpedo comprising a shell, a plunger therein, a passage for admitting compressed air to the under side thereof, a restricted communication admitting compressed air to 50 the upper side thereof, a frangible part communicating with said upper side, and means for rupturing said part.

5. An ignition mechanism for an automobile torpedo comprising a pressure-actuated 55 movable part, a frangible capsule adapted to confine the pressure, a movable knife adapted to puncture said capsule, and a connection with the engine for moving said knife.

In witness whereof, I have hereunto signed my name in the presence of two subscribing witnesses.

FRANK M. LEAVITT.
